UNITED STATES PATENT OFFICE.

TAUBE DAVIS, OF NEW YORK, N. Y., ASSIGNOR TO FRANKLIN SIMON & CO., INC., OF NEW YORK, N. Y., A CORPORATION OF NEW YORK.

DESIGN FOR A COAT.

Application filed January 16, 1926. Serial No. 16,130. Term of patent 8½ years.

To all whom it may concern:

Be it known that I, TAUBE DAVIS, a citizen of the United States, and a resident of the city of New York, borough of Manhattan, in the county and State of New York, have invented a new, original, and ornamental Design for Coat, of which the following is a specification, reference being had to the accompanying drawing, forming part thereof, wherein the coat is distinguished by having a collar presenting a parallel rolled effect with ornamental stripes extending around the neck portion of the collar and agreeing in the color effect with ornamental V-shaped stripes arranged in a section on each side of the coat.

The coat is also distinguished by ornamental cuff stripes agreeing with the stripes on the collar and sides of the coat.

Figure 1 is a view of a coat substantially in side elevation with the upper part shown partly in perspective, the same being illustrated on a figure and showing my new design.

Figure 2 is a three-fourths front view of the coat shown in Figure 1, the same being also illustrated on a figure.

I claim:

The ornamental design for a coat, substantially as shown and described.

TAUBE DAVIS.
